UNITED STATES PATENT OFFICE.

GUSTAV HOCHSTADTER, OF CHICAGO, ILLINOIS.

DESIGN FOR A LABEL-BLANK.

40,435.

Specification for Design.

Patented Jan. 11, 1910.

Application filed November 13, 1909. Serial No. 527,961. Term of patent 7 years.

To all whom it may concern:

Be it known that I, GUSTAV HOCHSTADTER, a citizen of the United States, residing at Chicago, Cook county, in the State of Illinois, have invented a new, original, and ornamental Design for a Label-Blank, of which the following is a specification, reference being had to the accompanying drawing, forming part thereof, in which is shown a face view of a label-blank incorporating my said design.

In said drawing, the label blank is shown as of rectangular outline having rounded corners, and a plain border beaded at its inner side along its bottom edge and partly at each side of the label blank. At each of the lower rounded corners are shown crescent shaped ornaments of conventionalized foliage. The background of the label blank is shown as representing a coarse woven fabric. At about the center of the label blank is displayed a shield crossed by two parallel diagonal bars contrasting with the body of said shield. In the center of said shield is arranged a circular field bearing the representation of a swastika cross. In superposition to the shield is shown a crown, between which and said shield a jewel or circular ornament is interposed. From the

sides of said jewel extend, in opposite directions, ornaments of conventionalized foliage in such a manner as partly to inclose the shield and also to support inward-turning, curved or crescent shaped ornaments placed in the opposite upper corners of the label blank. The representation of a flower is shown in each of said crescent-shaped ornaments, having its stem and foliage merging with the inner, lower ends of said crescent-shaped ornaments. In the center of the upper edge of the label blank is placed a trefoil ornament from which extend, in opposite directions, as far as the point of said crescent-shaped ornaments, sprays of conventionalized foliage. At each side of the lower half of the label blank, depending from the conventionalized foliage extending from opposite sides of the shield, are displayed a plurality of parallel chains, each of which supports a five pointed star as pendant.

I claim—

The ornamental design for a label blank as herein shown and described.

GUSTAV HOCHSTADTER.
